SELF-ALIGNING SLEEVE FOR PRESSURE-
TYPE GAS BURNERS AND THE LIKE

Charles M. Guy, Pittsburgh, Pa., assignor to Carnegie-Illinois Steel Corporation, a corporation of New Jersey

Application September 14, 1948, Serial No. 49,146

2 Claims. (Cl. 158—109)

1

This invention relates to pressure-type gas burners for blast furnace stoves and more particularly to an adjustable packing sleeve for such burners.

Operation of a blast furnace requires the use of an air blast, heated, for efficient furnace operation, to a high temperature, generally about 1000° F. The heating of the air blast is carried on in blast furnace auxiliary equipment commonly termed "stoves" and is effected by passing the air blast through a brick checkerwork in the stove, from which the air blast receives heat under a regenerative principle well known to those versed in the art, prior to entering the blast furnace. Since the brick checkerwork in stoves is alternately heated by the products of combustion of a gaseous fuel, usually blast furnace gas, in their passage from the blast furnace to the open and cooled by the passage of air in an opposite direction under pressure, a system of burners adapted to be connected in gas-tight manner with the stoves when they are in the "on-gas" cycle is required. When the stoves are "on-blast," that is, when air is passing through the checkerwork on the way to the furnace, the gas burners are usually retracted from the stoves.

The burners in use today are of the pressure-type having an integral air blower and a gas inlet leading to a chamber wherein the gas is mixed in the proper proportion with the air drawn in by the air blower. The mixed fuel passes out through a nozzle projecting from the burner into a gas port in the side of the stove.

For efficient operation it is essential that the connection between the nozzle and the stove port be gas-tight to prevent leakage of the fuel mixture while the stoves are "on-gas." It frequently occurs in practice, however, that the continual heating and cooling of the stove results in gradual misalignment of the stove gas port flange and the nozzle of the burner. Since prior to my invention, no means were provided to compensate for this misalignment, considerable leakage of gas through the resultant opening was experienced.

As is well known, blast furnace gas contains approximately 27% carbon monoxide and is therefore, noxious and extremely dangerous. The leakage of this gas into the atmosphere at or near ground level has been the cause of numerous fatalities or near fatalities among blast furnace workers.

It is accordingly an object of my invention to provide a self-aligning packing sleeve for blast furnace stove gas burners which will auto-

2

matically maintain the proper alignment and seating of the nozzle of the burner against the flange of the stove gas port at all times to thereby prevent leakage of the fuel mixture.

5 This and other objects will be apparent from the following specification when read in conjunction with the attached drawings, wherein:

Figure 1 is a side elevation partly in longitudinal section; and

10 Figure 2 is an enlarged sectional detail.

Referring more particularly to the drawings, reference numeral 2 indicates a conventional type blast furnace stove gas burner having a nozzle 4 projecting from its forward end and extending toward the flange 6 of a gas port 8 in the side of a blast furnace stove S.

The self-aligning packing sleeve of my invention consists of an adjustable cylindrical member 10 slidably mounted around the circumference of the burner nozzle 4; a packing ring 12, made of flexible material, slidably mounted circumferentially around the outer end of the cylindrical member 10 and projecting therefrom; a collar 14, which supports packing ring 12, 20 mounted around the outer surface of the cylindrical member 10 adjacent and partly enclosing packing ring 12; and a stop ring 16 fixedly mounted, by means of a shrink fit, around the circumference of cylindrical member 10 and spaced rearwardly of collar 14.

25 A longitudinal bolt hole 18 is provided through stop member 16. Extending through bolt hole 18 is a tap bolt 20 having its forward end threaded into collar 14. The diameter of bolt 20 is less than the diameter of bolt hole 18 and the longitudinal movement of the tap bolt 20 is limited by means of a pair of lock nuts 22 threaded on the end of the tap bolt projecting adjacent stop ring 16.

30 40 A compression spring 24 is provided around that portion of tap bolt 20 which is intermediate collar 14 and stop ring 16. Spring 24 bears with its one end against collar 14 and its other end against stop ring 16. I have found it preferable to use eight of the spring assemblies, consisting of tap bolt 20, lock nuts 22, and spring 24, spaced equidistantly around the periphery of cylindrical member 10.

45 50 In order to prevent any gas leakage between cylindrical member 10 and nozzle 4, the rearward end of cylindrical member 10 is enlarged to provide a substantial annular space 25 between the under side of the rearward end of member 55 10 and the outer surface of nozzle 4 and a con-

tinuous packing ring 26, made of flexible packing material, is disposed therein.

Bolted to the rearward end of cylindrical member 10 by means of tap bolts 27 is a gland 28 which encircles the periphery of nozzle 4. Gland 28 is provided with a flange portion 30, adjacent packing ring 26, which functions to hold said packing ring in position. Rigidly attached to the bottom portion of cylindrical member 10 is a rearwardly extending arm 31 carrying a rack 32. Disposed below rack 32 and in engagement therewith is a pinion 34. Keyed to the shaft carrying pinion 34 is a hand-wheel 36 whereby the pinion may be manually rotated to move the packing sleeve toward and away from the port 8.

In operation, before the blast furnace stove is put on "on-gas" cycle, that is, the period when the brick checkerwork of the stove is heated, hand-wheel 36 is rotated to move cylindrical member 10, by means of rack and pinion 32 and 34, into abutting position against flange 6 of gas port 8 to compress the springs 24. In this position packing ring 12 provides a continuous seal around the forward end of cylindrical member 10 and flange 6. Packing ring 12 is maintained in position automatically at all times by means of compression springs 24 constantly urging collar 14 in the forward direction to hold the packing ring 12 against flange 6. Thus an effective gas seal is maintained even though the forward end of cylindrical member 10 may be forced out of tightly abutting position with flange 6.

While one embodiment of my invention has been shown and described it will be apparent that other adaptations and modifications may be made without departing from the scope of the following claims.

I claim:

1. A packing sleeve for a gas burner having a fuel nozzle projecting from the end thereof comprising a cylindrical member slidably mounted circumferentially around said nozzle, a packing ring slidably mounted around the outer surface of said cylindrical member and projecting from the forward end thereof, a collar slidably mounted around said cylindrical member adjacent said packing ring, said packing ring being supported by said collar, a plurality of resilient means mounted around said cylindrical member at spaced intervals urging said collar supported packing ring forward beyond the forward end of said cylindrical member, said resilient means consisting of a stop ring fixedly mounted around said cylindrical member in spaced relationship with said collar, said stop ring having a longitudinal bolt hole therethrough, a tap bolt having a diameter slightly less than the diameter of said bolt hole extending through said bolt hole and having its forward end threaded into said collar, and its other end projecting rearwardly of said stop ring, the longitudinal movement of said tap bolt being limited by a pair of lock nuts

threaded around its rearwardly projecting end adjacent said stop ring, and a compression spring mounted around said tap bolt intermediate said collar and said stop ring bearing against said collar on its one end and against said stop ring on its other end.

2. A packing sleeve for a gas burner having a fuel nozzle projecting from the end thereof comprising a cylindrical member slidably mounted circumferentially around said nozzle, said cylindrical member being adapted to move longitudinally on the outer surface of said nozzle, means for moving said cylindrical member longitudinally, a packing ring slidably mounted around the outer surface of said cylindrical member and projecting from the forward end thereof, a collar slidably mounted around said cylindrical member adjacent said packing ring, said packing ring being supported by said collar, a plurality of resilient means mounted on the circumferential surface of said cylindrical member at spaced intervals adjacent said collar urging said collar supported packing ring forward beyond the forward end of said nozzle, said resilient means consisting of a stop ring fixedly mounted around said cylindrical member in spaced relationship with said collar, said stop ring having a bolt hole therethrough, a tap bolt having a diameter slightly less than the diameter of said bolt hole extending through said bolt hole and having its forward end threaded into said collar and its other end projecting rearwardly of said stop ring, the longitudinal movement of said tap bolt being limited by a pair of lock nuts threaded around its rearwardly projecting end adjacent said stop ring, and a compression spring mounted around said tap bolt intermediate said collar and said stop ring bearing against said collar at its one end and against said stop ring at its other end, a lock ring slidably mounted around said nozzle adjacent the rearward end of said cylindrical member, said lock ring and said cylindrical member being connected by bolt means, and a stuffing gland disposed subjacent the rearward end of said cylindrical member, said gland being held in position intermediate said cylindrical member and the outer surface of said nozzle by said lock ring.

CHARLES M. GUY.
